ATTORNEY

UNITED STATES PATENT OFFICE.

WILLIAM W. LOWREY, OF STATEN ISLAND, NEW YORK.

DESIGN FOR A BOTTLE.

SPECIFICATION forming part of Design No. 24,581, dated August 20, 1895.

Application filed July 9, 1895. Serial No. 555,444. Term of patent 3½ years.

To all whom it may concern:

Be it known that I, WILLIAM W. LOWREY, a citizen of the United States of America, and a resident of Staten Island, Richmond county, 5 State of New York, have invented a new and useful Design for a Glass Bottle, of which the following is a specification.

In the drawings, Figure 1 represents a front elevation showing my design. Fig. 2 represents a sectional plan view taken on line X X. Fig. 3 is a side view of Fig. 1, and Fig. 4 is an inverted plan view of Fig. 3.

The leading feature of my design consists in two flat plane surfaces forming the broad sides of the bottle. The upper line of said flat planes is formed by a curved or arched line, each end of which joins the vertical corners, each of the latter joining, as they do, a right angle. The aforesaid broad sides of the bottle 15 are united by a vertically-arranged convex surface, the upper edges of which are either arched or curved. The ends of the latter connect or join with the aforesaid flat plane surfaces, thus giving the top surface of the bottle a convex appearance. Upon the surface 20 of the latter is arranged a correspondingly-shaped tablet, whose contour is concentric with that of the body of the bottle. The base-line of the vertically-arranged flat plane surfaces 25 and those of the vertically-arranged convex surfaces terminate in beveled surfaces, the latter of which forms the base of the bottle. It will be obvious that a bottle made to cor-

respond with the design herein shown will present a peculiar combination of highlights, 35 together with prismatic effects.

Similar letters and figures refer to similar parts throughout the drawings, in which—

A represents the bottle, whose front or broad sides are formed by the flat plane surfaces b, 40 having their upper edge c formed by a curved or arched line, the ends of the latter ending at the corners g, which also forms the vertical side edges of the first plane surfaces b, aforesaid. The side or edge of the bottle is formed 45 by the vertical convex e, the latter terminating in a plane surface f, forming the right-angle corner g. The top of the bottle is of a convex shape, having a tablet i integral therewith and concentric with the contour of the 50 body of the bottle, said tablet having integral therewith the neck k. The base-line 2 of the structure terminates in beveled surfaces l, whose corners terminate in small beveled planes m.

55

What I claim is—

The design for a glass bottle substantially as herein shown and described.

In testimony that I claim the foregoing as my invention I have signed my name, in presence of two witnesses, this 19th day of April, 1895.

WILLIAM W. LOWREY.

Witnesses:

JOHN YSASI,
D. S. DOLBEAR.
